UNITED STATES PATENT OFFICE.

OTTO F. OSTERGREN AND ALEXANDER K. SCHAAP, OF RICHMOND,
VIRGINIA.

DESIGN FOR A GARMENT-PROTECTOR.

SPECIFICATION forming part of Design No. 20,548, dated March 3, 1891.

Application filed December 8, 1890. Serial No. 373,962. Term of patent 14 years.

To all whom it may concern:

Be it known that we, OTTO F. OSTERGREN and ALEXANDER K. SCHAAP, both citizens of the United States, residing at Richmond, in the county of Henrico and State of Virginia, have invented and produced a new and original Design in Garment-Protectors, of which the following is a full, clear, and exact specification, reference being had to the accompanying drawings, in which—

Figure 1 is a perspective view of our design, and Fig. 2 is a plan view thereof.

Our invention has relation to garment-protectors such as may be employed on sleeves or trousers.

The protector consists of a flat strip of material of substantially circular configuration, the two ends of which do not quite meet and are reversely curved upon themselves, as indicated at A A.

The leading feature of our design is the flat strip circular in configuration and having at its approximating ends the reverse curved terminals A A. It will thus be seen that we provide a garment-protector of most graceful outline.

Having described our invention, what we claim, and desire to secure by Design Patent, is—

The design for garment-protector herein shown and described.

In testimony whereof we have hereunto affixed our signatures in the presence of the two subscribing witnesses.

OTTO F. OSTERGREN.
ALEX. K. SCHAAP.
